UNITED STATES PATENT OFFICE.

WILLIAM S. REED, OF LEOMINSTER, MASSACHUSETTS.

COMBINATION TOY.

SPECIFICATION forming part of Letters Patent No. 288,664, dated November 20, 1883.

Application filed April 21, 1883. (No model.)

To all whom it may concern:

Be it known that I, WILLIAM S. REED, of Leominster, in the county of Worcester and State of Massachusetts, have invented certain 5 Improvements in Combination Toys, of which the following is a full, clear, and exact description, reference being had to the accompanying drawings, making part of this specification, in which—

10 Figure 1 is a perspective view of a miniature folding desk and easel, with the figure of a student represented in solving a problem on a blackboard. Fig. 2 is a view of the desk, easel, and blackboard in a position ready to be packed in a box.

15 This invention consists in an adjustable toy easel, in combination with an adjustable toy desk-leaf pivoted thereto, and having a drawer sliding thereunder, if desired, the various inclinations of the easel and desk-leaf being regulated at pleasure, and serving to support a blackboard or canvas frame on which lessons, problems, paintings, or drawings may be represented, the several portions being arranged to fold compactly together when not in use or to be packed in a box for transportation.

20 To enable others to understand my invention, I will proceed to describe the manner in which I have carried it out.

25 In the said drawings, A A represent two long front legs having their tops inclined backward and toward each other, being united by an ornamental cap, a.

30 B B are two shorter legs, hinged at their upper ends, b, to the rear of the front legs, A A, the lower ends of the shorter legs being held together by a connecting-rod, c.

35 C C are two cleats, the inner end of each being pivoted at d to the outside of one of the rear legs, B, and the outer end of the cleat being provided with notches e, which enable it to be hooked over a pin, h, projecting from the outside of a front leg, A, and by which 40 means the desired inclination may be given the easel.

45 D is a flat leaf to be used as a desk, and secured to the tops of two side pieces, i i, (shown in Fig. 1,) pivoted to the inside of the legs A A, and provided with holes k, for the recep-

tion of pins l, projecting from arms m, pivoted at n to the inside of the legs A A, near their bottoms, these arms m, with their pins l, in connection with the side pieces, i, and their holes k, affording a convenient means for adjusting the desk-leaf D to any desired inclination. Under the leaf slides a drawer, G, for containing miniature crayons, brushes, rulers, paints, palettes, books, &c.

55 H is a blackboard, the bottom of which rests on the inclined leaf and the upper edge against the front of the legs A A, in an accessible position for the student I to figure, write, or draw thereon. A framed canvas may be substituted for the blackboard. The figure 60 of the student is represented with a crayon in hand, in the act of solving an arithmetical problem.

65 r r represent books, and s a pair of dividers resting on the desk-leaf.

70 From the foregoing it will be seen that the inclinations of the easel and desk may be regulated with facility, and when not required for use may be compactly folded, and, with the blackboard and other attachments, be in a 75 position for stowing within a box.

75 The manipulation of the within-described toy diverts the child, besides educating the mind in mechanical construction.

I claim—

80 1. As an improvement in toys, the combined easel and desk capable of adjustment, substantially as described.

85 2. The legs A A and B B, pivoted together, and provided with notched cleats C C and pins h h, for adjusting the inclination of the front legs, A A, in combination with the desk-leaf D, pivoted to the legs A A, and provided with a means of adjusting its inclination, as set forth.

90 3. A miniature blackboard or canvas-covered frame, in combination with a toy easel and desk, as specified.

Witness my hand this 21st day of March, 1883.

WILLIAM S. REED.

In presence of—

JAS. W. CHAPMAN,
N. W. STEARNS.
